UNITED STATES PATENT OFFICE.

HARRY S. KUHN, OF WAYNESBORO, PENNSYLVANIA.

VICE SCREW AND HANDLE.

1,150,042.

Specification of Letters Patent. Patented Aug. 17, 1915.

Application filed November 20, 1914. Serial No. 873,186.

To all whom it may concern:

Be it known that I, HARRY S. KUHN, a citizen of the United States, residing at Waynesboro, in the county of Franklin and State of Pennsylvania, have invented a new and useful Vise Screw and Handle, of which the following is a specification.

The present invention appertains to a screw and handle for vises, and aims to provide a novel and improved means upon the shank of the screw for holding or carrying the handle or tommy-bar, whereby the handle may be conveniently adjusted or set at various angular positions relative to the screw, and about the axis thereof, when circumstances render it desirable or necessary.

Another object of the invention is to provide unique means for assembling the screw and handle or tommy-bar, whereby the handle may be employed for forcibly rotating the screw in either direction, and whereby the handle may be adjusted angularly about the axis of the screw when desired, and without detracting from the efficiency of the device.

Another object of the invention is to provide a device of the character indicated, which will also tend to hold the handle or tommy-bar against slipping or sliding movement longitudinally of itself.

It is also within the scope of the invention, to provide a device for assembling the screw and handle or tommy-bar, which will be comparatively simple, durable and compact in construction, which will be inexpensive and easy to manufacture, and which will be convenient, practical and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a front view of one form of the invention, a part of the handle or tommy-bar being broken away. Fig. 2 is a longitudinal section through the said device, parts being broken away.

In carrying out the present invention,

there is provided a tubular head 1 having its inner end secured in any suitable manner upon the shank 2 of the screw 3, the screw being illustrated as being detached from the body of the vise, since it is well known how the screw is applied to the vise, and this need not be illustrated or described.

The enlarged head 1 carried by the outer end of the screw is provided with a socket or recess 4 extending longitudinally thereof from its outer end, and the outer end or end face of the head 1 is provided with an annular series of diametrically opposite pairs of radial notches 5 extending from the periphery of the head 1 to the socket or bore 4.

A plug 6 is slidable snugly within the socket or bore 4, and is provided adjacent its outer end with a diametrical or transverse bore or opening 7 through which the diametrical handle or tommy-bar 8 is slidably engaged to be shifted laterally as usual. The handle 8 is engageable in the notches 5 whereby the handle may be swung to rotate the screw 3 in either direction.

A sleeve or ring 9 is mounted slidably and rotatably upon the periphery of the head 1 and surrounds the notches 5, and the sleeve 9 is provided with diametrically opposite apertures 10 adjacent its outer end through which the diametrical handle or tommy-bar 8 is passed.

The head 1 is provided with an inwardly facing peripheral shoulder 11 between the ends of the sleeve 9 and spaced inwardly from the notches 5, and the inner end of the sleeve 9 is provided with an inturned annular flange or lip 12 slidably engaging the head 1 at a point inwardly from the shoulder 11. A coiled wire expansion spring 13 is disposed between the sleeve 9 and head 1 and has its endmost convolutions bearing against the shoulder 11 and flange 12, to yieldably slide the sleeve 9 inwardly.

Ordinarily the handle or tommy-bar 8 is drawn into a pair of diametrically opposite notches 5, since the sleeve 9 through which the handle 8 is engaged, is forced inwardly through the influence of the spring 13. Thus, the handle or tommy-bar 8 may be swung for forcibly rotating the screw 3 in either direction for adjusting the jaws of the vice (not shown). Now, if it is desirable or necessary to change the angular position of the handle 8 with respect to the screw 3, this may be readily accomplished

by pulling or forcing the handle 8 longitudinally outward so that it is withdrawn from the notches 5, and which will enable the handle to be swung in one direction or 5 the other, without rotating the screw 3, so that the handle 8 may be readjusted and then when released, will be drawn into the respective notches 5 under the influence of the spring 13 to again enable the handle to 10 be swung for rotating the screw. The handle 8 being engaged through the slidable sleeve 9 and the plug 6, will cause the handle to be guided for true longitudinal movement, and the said sleeve and plug will prevent the handle binding or swinging in 15 other than in a plane at right angles to the axis of the screw. Furthermore, the sleeve 9 being yieldably forced inward by the tension of the spring 13, will tend to bind the handle upon the bar 8 between the outer portions of the apertures 10 of the sleeve 9, and the bottoms or seats of the notches 5, to prevent the handle from sliding or slip- 20

ping longitudinally of itself, especially when the handle is arranged vertically or 25 nearly so.

What is claimed is:

In a device of the character described, a screw having at its outer end an enlarged head formed with a peripheral shoulder, 30 and with radial notches in its end face, a sleeve slidable upon the periphery of the head and formed at its inner end with an internal flange, a coiled expansion spring confined between the said flange and the shoulder, and a diametrical handle passing through the outer end portion of the sleeve and engageable in said notches. 35

In testimony that I claim the foregoing as my own, I have hereto affixed my signature in the presence of two witnesses. 40

HARRY S. KUHN.
